SICKLE GRINDER

Conrad Stadick, New Ulm, Minn.

Application January 14, 1953, Serial No. 331,135

1 Claim. (Cl. 51—72)

My invention relates to sickle grinders, and has for its primary object the provision of a novel mechanism for the sharpening of generally triangular cutting blades of a sickle without removing same from the sickle bar.

A still further object of my invention is the provision of a device of the class described which is provided with a power driven grinding wheel which is so mounted as to enable the operator to quickly and easily adjust the position of same so as to obtain any desired angulation or position of the cutting faces thereof.

A still further object of my invention is the provision of a novel means for suspending or mounting the sickle bar, including yielding means, whereby any desired position of the cutting blades, with respect to the grinding wheel, may be quickly and easily arrived at.

A still further object of my invention is the provision of a device of the class described which is inexpensive and simple in construction, yet durable in use.

A still further object of my invention is the provision of a device of the class described which is extremely easy to operate, yet is highly efficient in use.

The above and still further objects of my invention will become apparent from the following detailed specification, appended claim, and attached drawings.

Referring to the drawings, wherein like characters indicate like parts throughout the several views:

Fig. 1 is a view in plan of my novel structure, one position of the parts thereof being shown by dotted lines;

Fig. 2 is a view in front elevation of the structure of Fig. 1; and

Fig. 3 is a view partly in end elevation and partly in vertical section, as seen from the line 3—3 of Fig. 2.

Referring with greater particularity to the drawings, the numeral 1 indicates a horizontally-disposed generally rectangular frame made up of angular, parallel, front and rear members 2 and 3, respectively, and joining end members 4 and 5. Preferably and as shown, the frame 1 is supported from the floor by means of legs 6 at each corner. The upstanding sides 7 of the angular front and rear members 2 and 3, respectively, define an elongated guideway in the nature of rails. Carriage 8, preferably and as shown in the nature of a rectangular plate, has laterally-spaced pairs of trunnions 9 projecting outwardly from opposite sides. Journalled for rotation on the trunnions 9 are rollers 10 having concave peripheral surfaces 11 adapted to receive the upstanding rail-acting sides 7 of the frame members 2 and 3 therein. In this manner, the carriage 8 is mounted for longitudinal sliding movements with respect to the frame 1. In order to manually impart reciprocal movements to the carriage 8 along the tracks 7, I provide a conventional chain 12 secured at its opposite ends to frame members 4 and 5, respectively, and positioned therebeneath. Depending from the carriage 8 are a pair of laterally-spaced bearing legs 13, through which passes for rotation a shaft 14 having a handle 15 at its forward end, and a sprocket 16 at its rear end. As shown, sprocket 16 has meshing en-

2

gagement with the chain 12. End thrust of the shaft 14, with respect to the bearing legs 13, is prevented by screw-equipped collars 17. It should be obvious that rotation of the crank-acting handle 15 causes the sprocket 16 to travel on the chain 12, and to simultaneously move the carriage 8 longitudinally of the frame 1, the rollers 10 rolling upon the rail-acting sides 7 of the frame members 2 and 3.

A base plate 18 overlies the carriage 8 and is connected thereto for swinging movements in the plane thereof through the medium of a strap 19, which projects forwardly and has its free end 20 pivotally secured thereto through the medium of a nut-equipped bolt 21. Rigidly secured by welding or the like to the base plate 18 and projecting upwardly therefrom are a pair of laterally-spaced posts 22, through the upper ends of which projects a shaft 23. Mounted at their upper ends for swinging movements about the shaft 23 are a pair of laterally-spaced supporting legs 24. At the lower ends, the supporting legs 24 are angularly out-turned to provide supporting feet 25, to which, by means of threaded bolts or the like 26, is secured a motor-mounting plate or member 27. An electric motor 28 is secured to the motor mounting plate 27 by means of threaded bolts or the like 29. For the purpose of positioning the motor mounting member 27 and motor 28 in a desired position about the axis of the shaft 23, I provide a tongue 30 which is centrally slotted, as at 31, to receive a toothed locking bar 32.

Rigidly secured to the outer end of the drive shaft 33, by means of a nut 34 or the like, is an abrasive or grinding wheel 35, preferably and as shown having a beveled peripheral grinding face 36 thereon. It will be noted that the drive shaft 33 of the motor 28 is disposed at an oblique angle with respect to the shaft 23 upon which the legs 24 are pivotally mounted, and that the axis of the grinding wheel 35 intersects the axis of said shaft 23. It will also be observed that the axis of the pivot bolt 21 is substantially tangent to the peripheral surface 36 of the grinding wheel 35.

Projecting rearwardly from the frame member 3, one

each adjacent opposite ends thereof, are a pair of lugs 37 to which are rigidly secured a pair of standards 38.

A pair of horizontally-disposed supporting arms 39 have

their rearward ends slidably adjustably secured within heads 40, as indicated at 41. Heads 40 are slidably adjustably secured to the upper ends of the standards 38, as indicated at 42. This arrangement makes pos-

ible horizontal and vertical adjustments of the arms 39 with respect to the standards 38. The free ends of the arms 39 terminate adjacent the vertical plane of the front edge of the frame 1, preferably and as shown in forwardly spaced relation thereto. A pair of coil

55 springs 43 are connected one each at their upper ends to the free ends of the arms 39, as indicated at 44. At their lower ends, the springs 43 have hooked engagement with the upper ends of sickle bar clamping members, identified in their entirety by the numeral 45, and each including a vertically-disposed rod 46. Rods 46 are, as

60 shown, bent backwardly upon themselves at their lower ends, as indicated at 47, to nestingly receive the rear end portion of a sickle bar 48. Slidably adjustably mounted on the upper end portions of the rods 46 are clamping

65 fingers 49, which are notched, as at 50, to receive the forward end portions of conventional triangular-shaped cutting knives 51, customarily secured to the sickle bar 48 in side by side relation by means of rivets or the like 52.

The thumb screws for releasably locking the fingers 49 to the rods 46 are identified by the numeral 53.

By the above described arrangement, it should be obvious that the peripheral grinding face 36 of the grind-

ing wheel 35 may be moved to any desired operative position without changing the distance therebetween and the axis of the pivot bolt. This is extremely important because different angular positions of the grinding face 36 are necessary for the effective and efficient sharpening of the angular faces of the cutting knives 51. Furthermore, it should be obvious that because of the yielding connection between the clamping members 45 and the arms 39, that the maximum degree of universal movement by the cutter bar at the grinding wheel is achieved. Obviously, a still further benefit of this yielding connection is that the operator is relieved of the necessity of carrying the weight of the sickle bar when sharpening the knives thereof, and needs only to guide and direct same.

In operation, the operator attaches the sickle bar 48 in the clamping members 45 with the cutting knives 51 positioned upwardly, as shown in Fig. 2. The carriage 8 is then positioned adjacent one end of the sickle bar 48 by manipulation of the crank handle 15. The sickle bar, under the yielding tension of the springs 43 may be readily tilted in opposite directions by raising and lowering either end, whereby to obtain proper and desired engagement of the converging knife-acting side edges of the cutting knives 51 with the peripheral surface 36 of the grinding wheel 35. The carriage 8 and grinding wheel 35 mounted thereon are advanced from tooth to tooth as desired; however, during the sharpening of the side edges of a given blade, or alternately during the sharpening of the diverging edges of adjacent blades, the carriage 8 and grinding wheel 35 remain fixed on the tracks 7.

My invention has been thoroughly tested and found to be completely satisfactory for the accomplishment of the above objects, and while I have shown a commercial embodiment of my invention, it should be obvious that same is capable of modification without departure from the scope of the invention as defined by the appended claim.

A grinder for sickle bars including a horizontally disposed frame defining an elongated guideway, a carriage mounted for sliding movements on said guideway, means for imparting reciprocal movements to said carriage on said guideway, a power operated grinding wheel on said carriage, a pair of laterally spaced standards secured to said frame and projecting upwardly adjacent the rear side of said guideway, a pair of generally horizontally disposed supporting arms one each secured to one of said standards and having their free ends terminating in a vertical plane forwardly of the front edge of said frame, a pair of vertically disposed, laterally spaced sickle bar clamping members, and coil springs connecting the upper end portions of said clamping members one each to the free ends of said supporting arms, said clamping members including vertically disposed rods, said rods being bent backwardly upon themselves at their lower ends to nestingly receive the rear end portion of said sickle bar, and slidably adjustable clamping fingers on said vertically disposed rods, said clamping fingers being provided with notches to receive the forward end portions of the cutting knives carried by said sickle bar.
